UNITED STATES PATENT OFFICE.

ISAAC E. HILL, OF HANNIBAL, MISSOURI.

ETHER DROPPER.

Application filed January 31, 1921. Serial No. 441,259.

To all whom it may concern:

Be it known that ISAAC E. HILL, a citizen of the United States, residing at Hannibal, in the county of Marion and State of Missouri, has invented certain new and useful Improvements in Ether Droppers, of which the following is a specification.

My invention relates to a dropper, and particularly to a means to dispense ether from cans to give a finished technic to ether administration as compared with the present unhandy methods followed by anesthetists.

In carrying out the invention I aim to provide an efficient and inexpensive article to attain the end stated and one employing a plate and an attaching device, the latter being preferably according to my preferred embodiment illustrated in accompanying drawings and hereinafter described.

In said drawings;—

Fig. 1 is a fragmentary view of a can adapted to contain ether, and having my dropper device in place thereon and being in side elevation;

Fig. 2 is a plan view of the parts of Fig. 1;

Fig. 3 is a plan view of the dropper device;

Fig. 4 is an inverted view of the dropper device, and

Fig. 5 is a central longitudinal section of the dropper device as on line 5—5 of Fig. 3.

Like reference characters designate like or similar parts throughout the different views.

Referring specifically to the drawings, 1 represents the usual type of ether containers, having a flange or projecting bead 2 around the mouth, and the latter being 40 closed by a stopple sheet or cover 3, of soft easy punctured material.

The invention utilizes a plate 4 of any suitable material, preferably metal and of any approved shape. As shown in the drawings, this plate tapers to a dropper proper 5, substantially pointed, and bent or curved outwardly as seen in Figs. 1 and 5. A length of resilient spring wire is employed and formed at the central portion into an arch 50 or clasp 6, from the ends of which spacing arms 7—8 extend. Portion 7 of said arms extend outwardly and serve to dispose the arms of the arch at a distance within and from the sides of plate 4 while portions 8 space the arch from the plate. The arch is bowed as shown at 9 in Fig. 5. Arms 10

of any desired shape extend from arms 7—8 and may be secured to the plate in any suitable manner, as by soldering as at 12.

In use, the can 1 at the cover 3, is punctured as usual by any suitable instrument to provide one or more outlets 13, and a vent opening 14. Instead of the anesthetist manipulating a finger over the openings, inserting a wick or grooved cork, my attachment may be used. This is accomplished by sliding the same over the mouth of the can, with the head 2 being received between plate 4 and arch 6. Said head is grasped by the arch frictionally and more effectively in view of the bow at 9, and the attachment while readily applied, will not be easily accidentally displaced. The cover or plate 4 is positioned over the opening 13 so as to receive the ether on its under surface. The ether when the can is tilted flows onto and down said under surface of the plate 4 to point 5 and then drops therefrom.

Merely the preferred embodiment has been illustrated and described hence changes within the spirit and scope of the invention may be resorted to.

I claim:—

1. An ether dropper comprising a plate having a portion thereof formed into a curved dropper lip, and a resilient wire secured thereon forming an arched clasp member adapted to movably hold the said plate on the upper surface of the mouth cap of the ordinary ether container in operative position.

2. An ether dropper comprising a plate having a dropping portion, a resilient arch secured thereon adapted to clasp the mouth cap of an ether container, securing portions connected to the plate, spacing means connecting the arch and securing portions, and means to guide the liquid towards the dropping lip, as and for the purposes set forth.

3. An ether dropper comprising a plate having a portion thereof formed into a curved dropping lip, means thereon to removably secure the said plate on the mouth of the ordinary ether can disposed within the longitudinal margin of the plate, and means to space said means from the plate and said means permitting the plate to be adjusted to any desired position relatively to the mouth cap of the said can, as and for the purposes set forth.

In testimony whereof I affix my signature.
ISAAC E. HILL.
